REGENERATIVE CHAMBER OR RETORT
OVEN FOR THE PRODUCTION OF GAS AND
COKEHeinrich Koppers, Essen, Germany, assignor, by
mesne assignments, to Koppers Company,
Pittsburgh, Pa., a corporation of DelawareApplication February 28, 1938, Serial No. 193,133
In Germany March 1, 1937

3 Claims. (Cl. 263—19)

The present invention relates to regenerative horizontal chamber or retort ovens for the production of gas and coke, and more particularly to a type of oven, in which the regenerators for preheating the combustion and the fuel gas are arranged underneath the coking chambers or retorts.

It is a well-known fact that during the operation of the plant, dust and other solid substances contained in the media, which are passed through the regenerators, tend to deposit in the regenerators of chamber- or retort ovens for the production of gas and coke. Such deposits are mainly found in those regenerators, serving for preheating the fuel gas, such as generator gas. Generator gas contains a considerable amount of dust and the like. As soon as the velocity of the gas flow, containing dust, falls below a certain value, the dust precipitates, especially on horizontal surfaces. Such faces are formed to a great extent in the chequerwork of the regenerators, and due to the fact that the gas velocity is comparatively low within the regenerators, there are easily formed deposits of dust and other materials, blocking-up the gas passages, and consequently the efficiency of the regenerator is reduced considerably. Further, the dust deposit acts as a heat insulation on the chequerwork of the regenerator and prevents the heat from passing into the chequerwork and out of same.

Now I have found, that dust deposits chiefly in the lower part of the regenerator chequer-work of horizontal chamber or retort coking ovens. The reason for this may be explained by the fact that the individual dust particles become temporarily somewhat pasty when the water evaporates from the surface of the dust particle as soon as the dust in the lower part of the regenerator attains a temperature above 100 degrees centigrade.

In order to eliminate the troublesome dust accumulations from the chequerwork of the regenerators, it is necessary to dismantle and clean the chequerwork from time to time, and this work is rather difficult and costs very much.

The main object of my present invention consists in the provision of such improvements in regenerators of horizontal chamber or retort ovens, which will permit the regenerators to be freed from dust and other deposits without considerable difficulty, and the chequerwork may be removed from the regenerators, in order to clean the latter.

My invention principally consists in support-

ing the upper part of the regenerator chequer-work separately, i. e. independently of the lower part of the chequerwork, in such a manner that the lower part of same may be removed from the regenerator without dismantling the upper part of the chequerwork beforehand or simultaneously.

The application of my invention renders it possible to clean the regenerators in a most easy way. Generally it is even unnecessary to cool down the regenerator completely, since the chequerwork in the lower part of the regenerator adjoining the sole channel passage of the regenerator, for outlet of the cooled waste gas media that has just given up its heat to the regenerator and inlet of cold gaseous media to be preheated, is heated up only to a comparatively low degree.

Another feature of my invention is to equip the lower part of the regenerator with a chequer-work consisting of refractory bricks each of which is provided with several openings or channels, through which the media may circulate.

It is very advantageous to use such bricks in the lower part of the regenerator for many reasons. For instance it is possible to build-up the chequerwork in that part of the regenerator that is to be dismantled frequently for cleaning purposes, with a relatively small number of individual bricks. Such bricks may easily be removed from the regenerator and replaced again, and this removing of the chequerwork is at any rate not as hard and troublesome as if the prismatic bricks, which have been used usually hitherto, and which are laid in the regenerator preferably in cross-bond, are used. Furthermore, the use of said bricks offers the possibility of reducing the wall thickness of the refractory brick body. The smaller the wall thickness of the brick of the chequerwork, the greater is the total heat exchange surface of chequerwork which can be built-in. Therefore, according to the present invention, the surface of the chequer-work may be increased in the lower part of the regenerator and the capacity of the regenerator will be improved considerably.

It is to be noted that the heat in the lower and cooler part of the regenerator is transferred substantially by convection alone, whereas in the upper and hotter part of the regenerator the heat transfer is assisted by radiation, which in most cases is very considerable. The heat transfer by means of convection greatly depends upon the area of the face giving-off or taking-up the heat. The larger this surface, the better the heat transfer by means of convection, whereas

for radiation depth of heat penetration is more effective.

Therefore, my invention further consists in an arrangement wherein the wall thickness of the regenerator chequerwork in the lower cooler convective part of the regenerator of horizontal chamber or retort ovens for the production of gas and coke is less, and the heat exchange surface per unit of space greater, than in the upper 10 hotter radian part of these regenerators.

In view of the above and to make apparent other objects and features of my present invention, I shall now describe a preferred embodiment of my present invention on the lines of the accompanying drawings, in which

Figure 1 is a vertical longitudinal section through a horizontal chamber oven for the production of gas and coke, built according to the present invention.

Figure 2 is a vertical section through the same oven taken transversely of Figure 1.

On the accompanying drawings, the chambers into which the coal to be carbonized is charged are marked 1. The chambers 1 are formed by 25 refractory brick walls 2, in which vertical heating flues 3, 3a are provided. The heating flues are connected in pairs at their upper ends, thus forming the so-called hair-pin or twin flues.

The regenerators 4, 5 are situated underneath 30 the coking chambers and heating flues. They are separated from each other in the middle of the oven by a partition 6. Between the regenerators on the one hand and the coking chambers and the heating flues on the other hand, there 35 are provided horizontal channels 7, 8. The channel 7 is connected by a sloped connecting channel 9 with the regenerator 5 and the channel 8 is connected with the regenerator 4 by means of the sloped channel 10. The channels 9, 10 cross 40 each other, as may be seen from the drawings. The regenerators are arranged side-by-side in a row underneath all the coking chambers of the coke oven battery.

Vertical channels 11, coming from the heating flues 3, 3a, lead to the regenerators, some 45 communicating through the horizontal channels 7, 8 which are in connection therewith. As can be taken from Figure 1, the heating flues 3a that are over regenerator 4 are communicably connected with the regenerator 5 through the horizontal channel 7. The flues 3 that are over regenerator 5 are, however, connected with the regenerator 4 through the horizontal channel 8.

The heating flues 3a that are situated above 55 the regenerator 5, are in direct communication with it. On the other side of the oven, the flues 3a are connected with regenerator 5 through the horizontal channel 7. Similarly, the flues 3 that are above regenerator 4 are in direct communication with it and on the other side of the oven 60 the flues 3 are connected with the regenerator 4 through the corresponding horizontal channel 8.

Figure 2 shows clearly that two regenerators, i. e., one regenerator 4 and one regenerator 5 are 65 situated underneath each oven chamber 1. The regenerators and the necessary horizontal channels 7, 8 are in combination with the heating flues of two heating walls.

The regenerators 4 and 5 operate in alternation with each other and, of said regenerators 4 and 5, the alternate regenerators G (see Figure 2) serve for instance for preheating the heating gas, for example generator gas, and the intermediate regenerators A serve for preheating the combustion air concurrently.

A vertical channel 11, coming from a gas regenerator and from an air regenerator leads into each heating flue 3 or 3a. It may be assumed that the regenerators 4 situated on the left side of the oven (see Figure 1) are supplied with air gas resp. through the openings 12. The media then rise upwards in their regenerators A and G, taking up the heat from the chequer-work provided in the regenerator, then distribute through the channels 11, through the horizontal 10 channel 8 and the adjoining channels 11 into the heating flues 3 on both sides of the battery, where they are burnt. The hot combustion gases pass upwards in the heating flues 3, flow downwards through the heating flues 3a and pass 15 through the channels 11 and through the horizontal channel 7, thereby entering the regenerator 5. The residual heat is transferred to the chequer-work of the regenerator 5 and the gases finally flow through the opening 13 into the 20 chimney.

As soon as the chequer-work of the regenerators 4 is cooled-down so that the media are no more pre-heated to the desired temperature, the direction of heating is reversed. The media 25 are then introduced through the openings 13 into the regenerators 5, which during the preceding heating period have been heated-up by the hot waste gases. From there the preheated media are distributed into the heating flues 3a, where 30 they are burned. They then flow through the heating flues 3 into ducts 11 and channel 7 into the regenerators 4, thence through the openings 12 into the chimney. The heating method is usual and well known to all those skilled in 35 the art of coke oven practice.

The distilling gases and vapours escaping from the coal which was charged into the coking chamber through the holes 14, arranged in the oven roof 15, are driven through the ascension 40 pipe 16 into the common collecting main. The coking chambers have openings at both sides which are closed by the doors 17. The coke produced in the chamber is discharged through these openings.

The construction of the regenerators is fully detailed and shown in Figure 2. The bottoms of the regenerators are provided with a pair of sole channels 18, leading to the openings 12, 13 resp. Openings 19 in the sole channels 18 lead 45 into the above situated chequer-work-space of the regenerator.

The lower portion of the space of the chequer-work is divided by vertical supporting walls 20. Perforated bricks 21 made of refractory material 5 fill-up the free space between the supporting wall 20 and the regenerator walls. These perforated bricks possess a multitude of openings 22 through which the media may flow. The bricks 21 may be removed separately or in groups 6 from the regenerators. For this purpose the front walls 23 (Figure 1) of the regenerators are built-up of removable brickwork, i. e., they may be taken out separately. Preferably, the front walls are constructed in the lower part of the regenerators in such a manner that they can be taken-off without loosening the connection of the front walls in the upper part of the regenerators. In this way, it is possible only to open the lower part of the regenerators, if necessary, and to remove from it the bricks 21 for 7 cleaning purposes.

Horizontal walls 25 are provided on the vertical supporting walls 20 and projections 24 on the regenerator walls. The chequerwork 26 for 7

the upper part of the regenerators is situated on these walls 25. This chequerwork preferably consists of common prismatic bricks, which are suitably laid in cross-bond one above the other loosely. A free space is likewise above the chequerwork 26. The media may collect in this free space from where they are distributed onto the chequerwork.

The bricks 21 provided in the lower part of the regenerators are manufactured suitably of a smaller wall thickness than the bricks in the upper space 26 of the chequerwork. The reason for this provision has already been fully explained in the foregoing.

I have now described in the above the present invention on the lines of a preferred embodiment thereof, but my invention is not limited in all its aspects to the mode of carrying it out as described and shown, since the invention may be variously embodied within the scope of the following claims.

I claim:

1. A coking retort oven regenerator unit comprising a regenerator chamber having an upper regenerator filler of refractory heat transfer bodies providing passages for diffusion of gas to be preheated from below vertically upwardly through the filler and of waste gas from above vertically downwardly through the filler in alternation, and lower sole-flue means at the base of the filler for distributing the gas to be preheated to, and for exhaust of waste gas from, the base of the filler; and in which the heat transfer bodies in the upper radiant zone of the

filler are composed of relatively thick bricks laid in open channeled relation one above the other loosely, and the heat transfer bodies in the lower convective zone of the filler are composed of a relatively smaller number of perforated bricks of larger size than those in the upper radiant zone per unit of area, each of which larger size brick is provided with a plurality of channels for diffusion of the gaseous media, and in which the bricks of the upper radiant zone are supported independently of those in the lower convective zone and the bricks in the lower convective zone are laid therein so as to be removable separately without dismantling the bricks in the upper radiant zone of the filler.

2. Apparatus as claimed in claim 1 and in which the wall thickness of the bricks in the lower convective zone of the filler is less than the thickness of the bricks in the upper zone.

3. Apparatus as claimed in claim 1 and in which the wall thickness of the bricks in the lower convective zone of the filler is less than the thickness of the bricks in the upper zone, and in which the bricks in the lower zone are divided by a vertical supporting wall provided with a horizontal wall at its top, and in which projections are provided on the regenerator chamber walls, the regenerator brick of the upper radiant zone being supported by such projections and the horizontal wall independently of the brick in the lower convective zone divided by the vertical supporting wall.

HEINRICH KOPPERS.
